UNITED STATES PATENT OFFICE.

CHARLES M. DONELSON, OF SALT LAKE CITY, UTAH TERRITORY.

ROTARY CHURN.

SPECIFICATION forming part of Letters Patent No. 364,398, dated June 7, 1887.

Application filed January 11, 1887. Serial No. 224,046. (No model.)

To all whom it may concern:

Be it known that I, CHARLES M. DONELSON, of Salt Lake City, in the county of Salt Lake and Territory of Utah, have invented certain new and useful Improvements in Rotary Churns; and I do hereby declare the following to be a full, clear, and exact description of the invention, such as will enable others skilled in the art to which it pertains to make and use it, reference being had to the accompanying drawings, which form part of this specification.

My invention relates to an improvement in rotary churning; and it consists in, first, a casting having bearings for the driving-shaft, which has a beveled gear-wheel upon its inner end, and a cavity or aperture which forms a bearing for the beveled pinion, which has a shank or prolongation that extends downward into the cavity, and into which shank the upper end of the dasher-shaft passes, the cavity having an annular groove at its bottom, so as to reduce friction, and a chamber, which is formed in the upper surface of the casting, around the beveled pinion, for the purpose of catching any wear or dust and preventing it from working through the bearing; second, in a churn, the combination, with the body provided with sockets, of the legs which have their extreme upper ends to pass into the sockets, and having shoulders upon which the chines of the churn-body rest, and the screw-rods which pass through diagonally-opposite legs for clamping them against the sides of the churn-body.

The object of my invention is to produce a cheap and simple casting which can be secured to one half of the lid, and which is constructed so as to form bearings for the operating mechanism in such a manner that the lid may be removed from the churn without disturbing the relative position of the mechanism; to provide the churn with legs for supporting it, and which can be readily detached therefrom; to catch any milk or cream which may work through the bearing to the top of the casting, and to provide clamps for securing the half-lids in position upon the top of the churn.

Figure 1 is a perspective of a churn embodying my invention. Fig. 2 is an enlarged side elevation of the operating mechanism.

Fig. 3 is a vertical section of the inner end of the casting. Fig. 4 is a plan view of the legs. Figs. 5 and 6 are detail views.

A represents a churn-body, which is of any desired shape, size, or construction, and which is supported upon suitable legs or trestle-work, as shown.

The lid or top of the churn is made of two pieces or halves, and upon one of these pieces or halves is secured the casting in which the operating mechanism is placed. This casting consists of the horizontal portion B, which rests flatly upon one half of the lid or cover and is secured thereto in any suitable manner. Extending upward from this flat horizontal portion B are the two vertical standards C, which form bearings for the driving-shaft D. The inner end of the casting has the downwardly-extending portion E, which has a cavity formed therein, as shown, for the purpose of forming a bearing for the beveled pinion F. Formed around the bottom of the cavity is the annular groove I, which reduces the bearing-surface of the lower end of the shank H, and hence reduces the friction of the pinion when revolving. The driving-shaft D has its outer end bent at right angles to its horizontal portion, so as to form a crank in the usual manner. Secured to the inner end of the driving-shaft D is the beveled gear-wheel G, which engages the pinion or gear F, which gives a rotary motion to the dasher-shaft when caused to revolve. The pinion or gear-wheel F is provided with a shank or prolongation, H, which extends downward into the cavity formed in the inner end of the casting, and rests upon the point J. When the driving-wheel G is caused to revolve and a rotary motion is imparted to the pinion F, the tendency is to force the pinion F downward, and this downward pressure causes a great friction of the lower end of the shank upon the bottom of the cavity. The bottom of the cavity being provided with the annular groove I, this frictional contact, which would otherwise be very great, is reduced to a minimum. Formed in the top of the casting, around the cavity which forms a bearing for the shank H, is the annular groove K, which forms a chamber for catching any wear or dust which is liable to occur from working through the cavity, and

is thus prevented from running back into the churn and spoiling the butter which is being churned.

Formed in the lower end of the shank H, 5 and passing only partially through it, is a square opening, L, for the reception of the upper end of the dasher-shaft M, which is also correspondingly shaped. The upper end of the shaft M passes snugly but loosely through 10 the lower end of the cavity, which forms a bearing for the shank H, and hence has no other bearing at its upper end than the shank itself. The lower end of the shaft M will be pivoted in a metallic plate which is secured to 15 the bottom of the churn in the usual manner.

By providing the casting with the portion E, having a cavity for the reception of the shank H of the beveled pinion, the lid can be removed at any time, and the casting with it, 20 without in any manner interfering with the relative position of the gear-wheels. By lifting upward upon the half-lid to which the casting is secured, the weight of the shaft M and the dasher will cause the upper end of 25 the dasher-shaft to withdraw from the hole L and allow the lid carrying the casting and the gearing to be quickly and readily removed or placed in position upon the top of the churn.

Secured to the side of the churn-body, near 30 its lower end, are the metallic sockets P, into which the upper ends of the legs Q are passed, bringing the shoulders R in contact with the chines of the body, and upon which all weight of the churn-body and its contents rests. 35 Passing through diagonally-opposite legs are the screw-rods S, which are provided for the purpose of drawing the legs toward each other and clamping them tightly against the sides of the body of the churn. As it is desirable 40 to manufacture the body of the churn of as thin material as possible, there is not sufficient thickness to hold screws large enough to enable the sockets P to sustain the weight of the churn-body, its contents, and the strain which 45 is necessarily brought upon it when in operation, and hence the shoulders, which support all of the weight, and the screw-rods S, are provided. By means of the screw-rods, which clamp the legs against the side of the churn, 50 and the shoulders R, the sockets P are relieved from all strain and weight and serve merely as guides for the upper ends of the legs. By loosening the tension of the screw-rods the legs can be readily and quickly detached from 55 the churn whenever desired, or can be applied to churn-bodies of different sizes. The lower ends of the legs are held in their proper relative position by means of suitable stays.

In order to hold the half-lids rigidly in their 60 proper position upon the top of the churn, a

suitable number of metal strips or rods, T, extend up the side of the churn and have their lower ends bent, as shown in Fig. 5, so as to pass under and up behind the chines. These strips are provided with holes for securing them to the side of the churn; but as the churn-body is constructed of thin material, large screws cannot be used, and hence it is absolutely necessary that these lower ends should pass under the chines, as shown, and 65 upon which all strain is brought. The upper ends of these strips are formed into hooks, which pass through eyes in the lower ends of the screw-rods U. The upper ends of the rods 70 U are provided with thumb-nuts for the purpose of clamping the lid upon the top of the churn to any desired degree. By having the strip T extend under the chines, as shown, all strain is brought upon these lower bent ends, and by having the rod U flexibly and 75 detachably connected to the strip T, when it is desired to remove the lid or cover from the top of the churn, it is only necessary to loosen the thumb-nuts but slightly, when they can be thrown to one side, as shown in dotted lines in 80 Fig. 1, and the lid removed. The half-lids are provided with a suitable number of slotted plates N, into which the upper ends of the rods U pass. 85

I am aware that sockets have been secured 90 to a body so as to receive the upper ends of the supporting-legs, and this I disclaim. My invention differs from this in passing screw-rods through the upper ends of the legs, so as to clamp the legs tightly against the body, and 95 thus enable both body and legs to be carried around together without any danger of their becoming separated, as would be the case if no such clamps were used.

Having thus described my invention, I 100 claim—

1. In a churn mechanism, the combination of the casting B, formed with bearings C, the downwardly-extending portion E, having a cavity therein and provided with the annular 105 groove I, and chamber K, with the shaft M, beveled pinion F, having the shank H, beveled gear-wheel G, and shaft D, substantially as described.

2. In a churn, the combination, with the 110 body provided with the sockets P, of the legs Q, having the shoulders R, and the screw-rods S, for clamping them tightly against the churn-body, substantially as set forth.

In testimony whereof I affix my signature in 115 presence of two witnesses.

CHARLES M. DONELSON.
